UNITED STATES PATENT OFFICE.

GEORGE JONNATHAN FORREY, OF CARLISLE, PENNSYLVANIA, ASSIGNOR
OF ONE-HALF TO S. L. DIVEN, OF SAME PLACE.

CAR-COUPING.

SPECIFICATION forming part of Letters Patent No. 601,643, dated April 5, 1898.

Application filed December 29, 1896. Serial No. 617,343. (No model.)

To all whom it may concern:

Be it known that I, GEORGE JONNATHAN FORREY, a citizen of the United States, residing at Carlisle, in the county of Cumberland and State of Pennsylvania, have invented a new and useful Car-Coupling, of which the following is a specification.

The invention relates to improvements in car-couplings.

10 The object of the present invention is to improve the construction of car-couplings and to provide a simple, strong, and durable one which will be capable of coupling automatically and which may be readily uncoupled from the tops or sides of cars.

15 A further object of the invention is to provide a car-coupling having a pivoted knuckle to cushion the same, so that the force of the blow incident to two cars coming together for 20 coupling will be received by the draw-bars instead of by the knuckles, and to permit the knuckles to have sufficient longitudinal movement or play to enable the cars of a train to be successively started.

25 Another object of the invention is to enable the car-coupling to uncouple automatically in event of the draw-head becoming disconnected from the draft mechanism and thereby prevent the draw-head from falling 30 upon the track and wrecking cars.

The invention consists in the construction and novel combination and arrangement of parts hereinafter fully described, illustrated in the accompanying drawings, and pointed 35 out in the claims hereto appended.

40 In the drawings, Figure 1 is a plan view of a car-coupling constructed in accordance with this invention. Fig. 2 is a side elevation of the same. Fig. 3 is a horizontal sectional view. Fig. 4 is a transverse sectional view. Fig. 5 is a front elevation of the draw-head. Figs. 6 and 7 are detail views illustrating the construction of the headed plug of the transverse spring.

45 Like numerals of reference designate corresponding parts in all the figures of the drawings.

1 designates a draw-head provided at one side with a forward extension or flange 2 and 50 having a horizontal opening 3 extending inward from the other side of the draw-head

and receiving an arm or shank 4 of a knuckle 5. The knuckle 5 interlocks with a corresponding knuckle similar to the pivoted knuckle of a Janney car-coupling; but the shank or arm 4 is pivoted at its rear end centrally of the draw-head by a vertical pin 6, which passes through a perforation of the shank 4 and which is arranged in upper and lower horizontal slots 7 of the top and bottom 60 of the draw-head. By this construction the car-coupling has a central draft, the pin being located in alignment with the center of the draw-bar 8.

The strain on the knuckles when cars are 65 in motion tends to hold them firmly closed, and they are positively held in a locked position by a transverse spring 9, which is adapted to yield to permit the knuckle to swing outward laterally of the draw-head in automatic coupling. As soon as the knuckles 70 pass each other the transverse springs 9 swing them inward and maintain them securely interlocked.

The arm or shank 4 of the knuckle has its 75 rear edge curved and provided with a rearwardly-extending lug 10, which is arranged in a recess 11 of a spring-actuated block 12. The block 12 is slidably mounted in the draw-bar 8, which is hollow, and it is provided with 80 a horizontal rod or pin 13, which is disposed longitudinally of the draw-bar and guided in a perforation of a flange or web 14. A spiral spring 15 is disposed on the rod or pin and interposed between the web or flange 14 and 85 the inner end of the block, and it is adapted to cushion the knuckle. The longitudinal spring holds the knuckle normally extended with the pin 6 at the outer ends of the slots 7, but in the accompanying drawings the 90 spring 15 is shown partially compressed with the pin 6 at the inner ends of the slots 7. The recess 11, which is arranged at the front end of the spring-actuated block 12, forms shoulders or stops which limit the swing of the 95 pivoted knuckle, and as the lug 10 is located a short distance from the pivot-pin 6 of the arm and the engaging portion thereof is situated such a distance in advance of the pin it will be apparent that only a comparatively 100 short recess is necessary to permit the engaging portion of the knuckle to swing into and

out of engagement with a corresponding knuckle.

The transverse spring which holds the knuckle in proper position has its outer end 5 engaging a projection 16 of the adjacent wall of the draw-head, and its other end receives a plug 17 and is arranged within a recess 18 of the adjacent side of the shank of the knuckle. The plug 17 is provided with a circular head 19, which engages a rib 20 of the knuckle. The rib is rounded and the circular head of the plug is provided with a curved groove 21 to conform to the configuration of the rib.

15 A chain 22, which is connected with the knuckle at the outer side thereof, is designed to extend to the car on which the draw-head is mounted and to be connected with an operating-lever for drawing the chain inward or 20 rearward to swing the knuckle laterally of the draw-head to effect the operation of uncoupling, and the chain is designed to be of such length that the knuckle will be automatically swung laterally and uncoupled 25 should the draw-bar become accidentally disconnected from the draft mechanism. By this construction a draw-head is prevented from being pulled out of a car and falling upon the track, and wrecks incident to such 30 obstructions are avoided.

The pin 6 is designed to be secured to the draw-head by a suitable key passing through its lower end, and a knuckle is designed to be provided with the usual link-opening and 35 coupling-pin perforation to enable the draw-head to be connected with the ordinary pin-and-link draw-head.

It will be seen that the car-coupling is simple and comparatively inexpensive in construction, that it is positive and reliable and 40 automatic in its operation, and that it is capable of coupling without necessitating persons going between cars and of automatically uncoupling should the draw-bar become 45 loose.

It will also be apparent that the knuckle has a central draft and is cushioned, and the blows incident to two cars coming together for coupling is received by the draw-heads 50 and not delivered upon the knuckles, and that the knuckles have sufficient play to permit cars to be successively started.

Changes in the form, proportion, and minor

details of construction may be resorted to without departing from the principle or sacrificing any of the advantages of the invention. 55

What I claim is—

1. In a car-coupling, the combination of a draw-head, a knuckle having an arm pivoted centrally of the draw-head, and a spring-actuated block engaging the arm of the knuckle to cushion the same and limiting the pivotal movement thereof, substantially as described. 60

2. In a car-coupling, the combination of a draw-head, a knuckle pivoted centrally of the draw-head and provided with a rearwardly-extending lug, and a spring-actuated block having a recess receiving the lug and forming opposite shoulders to limit the swing of the knuckle, substantially as described. 65

70 3. In a car-coupling, the combination of a draw-head provided at its top and bottom with centrally-arranged longitudinal slots, a knuckle provided with an arm having a perforation, a knuckle-pin arranged in said slots 75 and passing through the perforation of the knuckle, a spring-actuated block engaging the arm of the knuckle to cushion the latter and limiting the swing thereof, and a transverse spring engaging the knuckle, substantially as described.

4. In a car-coupling, the combination of a draw-head, a knuckle pivoted centrally of the draw-head and provided at its outer side with a recess, a rib arranged in the recess, a projection mounted on the draw-head opposite the recess, a transverse spiral spring having its outer end mounted on the projection, and a plug arranged in the inner end of the spiral spring and having a grooved head to engage 85 the said rib, substantially as described.

5. In a car-coupling, the combination of a draw-head, a knuckle having its arm pivoted centrally of the draw-head and capable of a limited movement longitudinally of the same, 90 a longitudinal spring for cushioning the knuckle, a transverse spring engaging the latter, and means for connecting the knuckle with a car, substantially as described.

95 In testimony that I claim the foregoing as my own I have hereto affixed my signature in the presence of two witnesses.

GEORGE JONNATHAN FORREY.
